(57) **CLAIM**

The ornamental design for a portion of a storage bin, as shown and described.

DESCRIPTION

FIG. 1 is an isometric view of a first embodiment of a portion of a storage bin from a first, top perspective.

FIG. 2 is a front view of the first embodiment of the portion of a storage bin.

FIG. 3 is a rear view of the first embodiment of the portion of a storage bin.

FIG. 4 is a left side view of the first embodiment of the portion of a storage bin.

FIG. 5 is a right side view of the first embodiment of the portion of a storage bin.

FIG. 6 is a top view of the first embodiment of the portion of a storage bin.

FIG. 7 is a bottom view of the first embodiment of the portion of a storage bin.

FIG. 8 is an isometric view of the first embodiment of the portion of a storage bin from a second, bottom perspective.

FIG. 9 is an isometric view of a second embodiment of a portion of a storage bin from a first, top perspective.

FIG. 10 is a front view of the second embodiment of the portion of a storage bin.

FIG. 11 is a rear view of the second embodiment of the portion of a storage bin.

FIG. 12 is a left side view of the second embodiment of the portion of a storage bin.

FIG. 13 is a right side view of the second embodiment of the portion of a storage bin.

FIG. 14 is a top view of the second embodiment of the portion of a storage bin.

FIG. 15 is a bottom view of the second embodiment of the portion of a storage bin; and,

FIG. 16 is an isometric view of the second embodiment of the portion of a storage bin from a second, bottom perspective.

Long-short broken lines illustrate boundaries that form no part of the claimed design. Features shown as evenly-sized broken lines form no part of the claimed design.

1 Claim, 16 Drawing Sheets
